CLAIM

(21) Appl. No.: **29/292,377**

The ornamental design for a stationary holder for personal electronic communication device (bed), as shown and described.

(22) Filed: **Oct. 10, 2007**

DESCRIPTION

(51) **LOC (9) Cl.** **03-01**

FIG. 1 is a top plan view of the stationary holder for personal electronic communication device (bed);

(52) **U.S. Cl.** **D3/201**

FIG. 2. is a right side view thereof, the left side view thereof is identical or a mirror image;

(58) **Field of Classification Search** D3/201,

FIG. 3. is a bottom view thereof;

D3/218, 215, 226, 272–273; D21/506, 521;

FIG. 4. is the front view thereof;

D6/393, 388–389, 392–395, 505–508; 5/53.1,

FIG. 5. is the rear view thereof; and,
FIG. 6. is a top view thereof indicating placement of Personal Digital Assistant (PDA).

5/907; D14/434

The broken line showing of environment in the drawings is included for the purpose of illustrating only and forms no part of the claimed design.

See application file for complete search history.
